UNITED STATES PATENT OFFICE.

GEORGE HENRY MAAS, OF MILWAUKEE, WISCONSIN.

BOX-FASTENER.

No. 909,919.

Specification of Letters Patent.

Patented Jan. 19, 1909.

Application filed June 29, 1908. Serial No. 441,006.

To all whom it may concern:

Be it known that I, GEORGE HENRY MAAS, a citizen of the United States, residing at Milwaukee, county of Milwaukee, and State 5 of Wisconsin, have invented new and useful Improvements in Box-Fasteners, of which the following is a specification.

My invention relates to improvements in devices for locking and sealing the cover retaining mechanism of shipping cases and it 10 pertains to that class for which Letters Patent, No. 878,215, was issued to me February 4, 1908.

By the device shown in such patent, the 15 hasp is pivotally connected with the cover and is adapted to engage laterally projecting lugs, which are rigidly connected with the walls of the case and said hasp is adapted, when in locking engagement with said projections, to be brought entirely beneath a 20 sealing plate by which access with the retaining hasp is prevented without breaking the seal, while by my present invention, the cover retaining hasp is pivotally connected with the walls of the case, and is adapted, 25 when in locking position, to engage the upper surface of the cover retaining plate at one side instead of beneath the seal.

The construction of my invention is explained by reference to the accompanying 30 drawings in which—

Figure 1 represents a vertical section of one side of the cover and case, together with the locking and sealing mechanism. Fig. 2 35 represents a bottom view of the seal removed from the case. Fig. 3 represents a fastening plate removed from the cover as it is cut preparatory to being bent into the required shape hereinafter described. Fig. 4 is a 40 front view, part in section, of the cover retaining hasp.

Like parts are identified by the same reference figures throughout the several views.

1 is a cover which is provided with an 45 aperture 2 for the reception of the cover retaining plate 3 and a seal 4. The plate 3 is secured to the inner side of the cover by a plurality of nails 5 and is provided with a central aperture 6 for the reception of the 50 seal. The cover retaining hasp comprises the laterally projecting and pivotally supporting arms 7, the vertical member 8, the respective sides of which are formed integrally with said arms and the retaining loop 55 9, which is adapted when in the locking position to engage the upper side of the plate 3.

The hasp is pivotally connected with the vertical walls 10 of the case by the keeper 11 within the central recess 11'. The keeper 11 is connected with the walls of the case by a plurality of nails or screws 12. The plate 3 is provided upon one side with a vertical standard 13, which is formed integrally therewith and is bent upwardly, as shown in Fig. 1, so as to engage the recess 14 formed in one side of the seal.

The seal comprises the horizontal plate 15, provided with central apertures 16 for the reception of the removing instrument and an annular collar 17, extending downwardly at right angles to the plate 15 and a plurality of angular fastening members 18, which members are formed integrally with or connected at their upper ends to said plate 15 and at their lower ends with said annular collar 17. It will be understood that when said plate 3 has been secured in place against the lower side of the cover 1 and said hasp has been pivotally connected with the walls 10 of the case by the keeper 11, as shown in Fig. 1, said seal being removed, the hasp is brought into lodging engagement with the plate 3, as shown in Fig. 1, when it is retained in such locked position by inserting the seal, as shown in Fig. 1, while said seal is retained in the aperture of said plate 3 by the retaining members 18.

It will be understood that preparatory to inserting the seal, the several retaining members 18 are bent at an angle to the circle described by said collar 17, whereby the outwardly projecting lugs 19 of said retaining members 18 are adapted to engage beneath the lower side of the plate 3 and thereby prevent said seal from being surreptitiously withdrawn from the cover. When, however, it is desirous to remove the cover, said retaining members 18 are broken and disengaged from the plate 3, whereby said plate is removed when the upper end of the hasp is disengaged from said fastening plate, whereby the cover is released and may be opened and removed from the case.

The plate 3 is provided with lugs 20, 20, 21 and 13. The lugs 20, 20 and 21 are first cut with a punch or die, as shown in Fig. 3, when the members 20, 20 and 21 are bent downwardly to the position shown in Fig. 1, when they serve as a support to the lower side of the plate 3 beneath the lug 9, whereby the plate 3 at such point is reinforced and prevented from being bent downwardly.

as it might otherwise be and the cover removed from the case. The lug 13 is adapted to be bent upwardly, as heretofore described and shown in Fig. 1, whereby it prevents 5 the seal from being turned in its bearings.

Having thus described my invention what I claim as new and desire to secure by Letters Patent is—

1. In a device of the described class, the 10 combination of a shipping case, a hasp pivotally attached to the wall of said case, a cover provided with an aperture for the reception of the protruding end of said hasp, a cover retaining plate provided with an 15 aperture of less diameter than the aperture of said cover, means for securing said retaining plate to said cover and a sealing plate adapted to close the aperture of said cover retaining plate and to retain said hasp 20 in locking engagement with said cover retaining plate.

2. In a device of the described class, the combination of a shipping case, a hasp comprising two parallel central members, the 25 lower ends of which are respectively folded back upon themselves and terminate outwardly in opposite directions at right angles to said parallel central members and adapted to serve as pivotal supports for the other 30 members of said hasp, the upper ends of said parallel members being provided with a lug adapted to engage the cover retaining plate, means for pivotally attaching said hasp to the walls of the case, a cover provided with 35 an aperture for the reception of the protruding end of said hasp, a cover retaining plate provided with an aperture of less diameter than the aperture of said cover, means for securing said retaining plate to said 40 cover and means for retaining said hasp in locking engagement with said cover retaining plate.

3. In a device of the described class, the combination of a shipping case, a hasp pivotally attached to the wall of said case, a cover provided with an aperture for the reception of the protruding end of said hasp, a cover retaining plate provided with an aperture of less diameter than the aperture 45 of said cover, means for securing said retaining plate to said cover, means for retaining said hasp in locking engagement with said cover retaining plate, and a sealing 50

plate supported from said cover retaining plate, provided with a plurality of inwardly 55 projecting resilient lugs, said lugs being adapted when said sealing plate is in place, to engage the underside of said cover retaining plate and thereby prevent said sealing plate from being removed and said hasp 60 from being thrown out of engagement with said cover retaining plate.

4. In a device of the described class, the combination of a shipping case, a hasp pivotally attached to the wall of said case, a 65 cover provided with an aperture for the reception of the protruding end of said hasp, a cover retaining plate provided with an aperture of less diameter than the aperture of said cover, means for securing said retaining plate to the inner surface of said cover, and a seal comprising a horizontal seal plate, an annular collar formed at right angles to said plate and a plurality of angular lugs connected at one end with said seal 70 plate and at their opposite ends with said annular collar, said seal plate being provided with apertures for the reception of a tool, by which said lugs may be broken, when desirous to remove the seal, all substantially 75 as and for the purpose specified.

5. In a device of the described class, the combination of a shipping case, a cover for said case, a locking device for securing said cover to said case, said cover being provided 85 with an aperture above said locking device, a fastening plate secured to said cover beneath said aperture and a seal for closing said aperture supported from said fastening plate above said locking mechanism, said seal comprising a horizontal seal plate, an annular collar formed at right angles to said plate, a plurality of angular lugs respectively connected at one end with said horizontal seal 90 plate and at their opposite ends with said 95 annular collar, said lugs being adapted to engage the lower side of said fastening plate and prevent said seal (without being broken) from being removed from said cover.

In testimony whereof I affix my signature 100 in the presence of two witnesses.

GEORGE HENRY MAAS.
